The ornamental design for a ceiling-mounted supply unit for a medical workstation, as shown and described.

DESCRIPTION

FIG. 1 is a front elevational view of a ceiling-mounted supply unit for a medical workstation, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged front elevational view of the lower right portion of the ceiling-mounted supply unit for a medical workstation shown in FIG. 1; and,

FIG. 8 is a top, front and right-side perspective view of the ceiling-mounted supply unit for a medical workstation.
